UNITED STATES PATENT OFFICE.

RUDOLPH CONRADER, OF ERIE, PENNSYLVANIA.

CONTROLLING DEVICE FOR FLUID-ACTUATED MOTORS.

1,113,956.

Specification of Letters Patent.

Patented Oct. 20, 1914.

Application filed November 14, 1910. Serial No. 592,345.

To all whom it may concern:

Be it known that I, RUDOLPH CONRADER, a citizen of the United States, residing at Erie, in the county of Erie and State of Pennsylvania, have invented new and useful Improvements in Controlling Devices for Fluid-Actuated Motors, of which the following is a specification.

This invention relates to controlling devices for fluid actuated motors, and consists in certain improvements in the construction thereof as will be hereinafter fully described and pointed out in the claims.

The invention is illustrated in the accompanying drawings as follows:

Figure 1 shows a central vertical section through the governor on the line 1—1 in Figs. 2 and 3. Fig. 2 is a section on the line 2—2 in Fig. 1. Fig. 3 is a section on the line 3—3 in Fig. 1.

1 marks the controlling valve body, 2 the diaphragm in the body, 3 the valve co-acting with the diaphragm, the valve being arranged to move axially through walls of the 25 diaphragm, 4 the cover for the valve body, 5 a gland on the cover, and 6 a valve stem secured to the valve. The governor frame 7 extends upwardly from the cover 4 and has the bearing sleeve 8 across its top, the 30 axis of the sleeve being horizontal. Bearings 9 and 10 preferably formed of Babbitt metal are arranged on the ends of this sleeve and a governor spindle 11 is journaled in these bearings. The drive pulley 12 is 35 fixed on the spindle by a set screw 13.

The carrier 14 for the governor is carried by the spindle 11 at the opposite end of the spindle from the pulley 12. It has a key 40 groove 15 in which the roller 16 operates to lock the carrier against rotation relatively to the spindle. The roller 16 is mounted on the spindle 11 by means of the pin 17.

The weights 18 (see Fig. 2) have the 45 shanks 19 which extend between the raised portion 20 on the inner face of the carrier 14 and the ears 21 extending inwardly from the surrounding flange of the carrier. The pins 22 extend through perforations 22^a of 50 the ears and the shanks 19 of the weights and into the carrier forming pivotal mountings for the weights 18. The ears 21 are each provided with two perforations, one of which in each ear I have marked 22^b. Pins 55 23 are arranged in the perforations 22^b and

the springs 24 extend from these pins 23 into slots 25 in the ends of the weights where they are secured by the pins 26, the springs 24 forming a part of the centripetal element of the governor. The perforations 22^b and 60 22^a are similar in relation to the other parts of the governor so that the weights may be reversed if desired, the pins 22 being arranged in the perforation 22^a and the pins 23 in the perforation 22^b for this purpose. 65 Pins 27 are arranged in the perforations 28 in the weights. These pins are parallel to the spindle 11. They are seated against a bearing piece 29 which is arranged in a socket in the side of the weight. The outer 70 face of this bearing piece is rounded and forms a bearing between the weight and the face of the carrier 14 so as to take a part of the thrust on the pin 27 as the weights are moved outwardly. The outer ends of the 75 pins are crotched at 30, and the links 31 are secured in the crotched ends by means of the pins 32. The opposite ends of the links extend between the ears 34 on a sleeve 35 and are pivotally secured thereto by 80 means of the pins 33. The sleeve 35 is slotted at 36 to permit the links to seat themselves in the sleeve when the weights are in their closed position. The spindle has the reduced end 37 for receiving the sleeve 85 35, and this forms the shoulder 38 which locks the sleeve against axial movement in one direction, and the washer 39 is arranged on the end of the spindle for locking the sleeve against axial movement in the opposite direction. A screw 40 is screwed into the end of the spindle, and holds the washer 90 in place.

It will be readily observed that the pins 27 being free to rotate in the weights, and the sleeve 35 being free to rotate on the spindle as the weights move outwardly, the swinging movement of the weights on the pins 22 is compensated for by the rotation of the pins 27 and the rotation of the sleeve 100 35 so that there is no binding of the parts. On the other hand, it will be observed that as the weights move outwardly, the sleeve 35 being locked against axial movement, the pins 33 are fixed against axial movement so 105 that with the outward swinging on the weights, the outer ends of the links must swing with the pins 33 as a center and base, and the result is that as the weights move outwardly, the carrier 14 and weights are 110

5 moved axially, and the governor is actuated through this movement of the carrier. This arrangement of weights and carrier permits of the complete housing of the carrier, there being preferably a plate 14^a on the outer face which completely incloses the links and weights.

10 In order to lubricate the parts within the governor, the part 37 is provided with a perforation 37^a and the screw 40 has the central perforation communicating with the perforation 37^a. A lateral perforation 37^b leads through the end 37 so that oil may pass from the opening 37^a to the bearing between the sleeve and extension 37. Laterals 37^c are arranged through the sleeve opposite the openings 31^a in the ends of the link so that oil moving through the laterals 37^c passes into the openings 31^a and thus lubricates the links. Some oil passes the links, and thus is carried into the carrier, and from this the lubrication of the other parts follows. There is also a lateral 11^a leading from the opening 37^a to the bearing 20 between the carrier and the spindle.

25 A lever 41 is pivoted on the pin 42 between the ears 43, the ears 43 extending from the frame 7. This lever has the threated end forming the arms 44. Rolls 30 45 are arranged on pins 46 at opposite sides of this arm. The pins 46 have the perforations 47 with lateral ends 48 for lubricating the rolls. The rolls engage a washer 49 on the face of the carrier.

35 A bar 50 is pivoted on a pin 51 between the ends of the arms 44. A spring base 52 is arranged in the center of the bar 50. A spring 53 is arranged between the base 52 and the base 54, the base 54 being on the end 40 of a screw 55. The screw 55 is arranged in a lug 56, and is provided with a handle 57, by means of which the screw may be actuated to adjust the spring 53, and the screw is locked in adjustment by the nut 58.

45 The spindle 11 has the circumferential grooves 59 which are filled by the annular shoulders 60 in the bearing 9 so as to prevent the endwise movement of the spindle under the pressure of the spring 53.

50 The lever 41 extends through an opening 61 in the frame 7, and is provided with a threated end 62, the arms of which are rounded, and extend each side of the spool 63, the rounded part of the arms engaging 55 the shoulders of the spool. The spool is internally screw threaded, and screwed on to the end of the stem 6. The stem can be adjusted in the spool to control the initial position of the valve, and locked in adjustment 60 by the jam nuts at its ends.

I have arranged an automatic stop device in the drawings, although this forms no part of the invention. A finger 107 is arranged on the spool 63 in the path of a finger 108, the finger 108 is carried on the

70 arm 109. The arm and the pin 110 is carried by the frame 7. The arm 109 is provided with a gear segment 111 which meshes a gear segment 112 on a lever 113. The lever 113 is pivoted on a pin 114 which is 75 on the frame 7. A roller 115 is arranged on the end of the lever and rotates on a flange 116. The flange is carried by a sleeve 117. An arm 118 is secured to the sleeve by means of a strap 118^a, and a clamping screw 118^b. 80 A rider pulley 119 rests normally on the driving belt 120. A spring 121 extends from a perforation 122 in the lever 113 to a perforation 123 in the frame 7, and is of sufficient strength to immediately close the valve 85 against the spring 52 when released. When the belt breaks, the pulley 119 drops carrying the flange 116 from under the roller 115, thus releasing the lever 113 and effecting the closing of the valve.

90 What I claim as new is:

1. In a controlling device for fluid actuated motors, the combination of a governor spindle; a carrier slidably mounted on the spindle; a weight forming the centrifugal element of the governor mounted on the carrier; and devices actuated by the weight for moving the weight and carrier bodily axially with the movement of the weight under the influence of centrifugal force.

95 2. In a controlling device for fluid actuated motors, the combination of a governor spindle; a carrier slidably mounted on the spindle; a weight forming the centrifugal element of the governor mounted on the carrier; a mounting locked against axial movement relatively to the shaft; and a connection between the mounting and the weight for moving the weight and carrier bodily axially on the shaft with a movement 100 of the weight under the influence of centrifugal force.

105 3. In a controlling device, for fluid actuated motors, the combination of a governor spindle; a carrier slidably mounted on the spindle; a weight pivotally mounted on the carrier, and having its axis parallel with the axis of the carrier; a mounting fixed against axial movement relatively to the spindle; and a link connecting the mounting with the 110 weight, and adapted to move the weight and carrier bodily axially relatively to the spindle with a movement of the weight under the influence of centrifugal force.

115 4. In a controlling device for fluid actuated motors, the combination of a governor spindle; a carrier mounted on the spindle; a weight pivotally mounted on the carrier, with its pivot parallel to the axis of the spindle; a mounting rotatively mounted on 120 the spindle; a link pivotally connected to the mounting; a connection rotatively mounted on the weight and connected with the link; and a device communicating the relative movement between the mounting 125 130

and the weight in an axial direction as the weight moves under the influence of centrifugal force to the valve.

5. In a controlling device for fluid actuated motors, the combination of a governor spindle; a carrier slidably mounted on the spindle; a weight pivotally mounted on the carrier with the axis of the pivot parallel with the axis of the spindle; a mounting 10 rotatively mounted on the spindle and locked against axial movement thereon; and a rotative connection carried by the weight; a link between the connection and the mounting.

15 6. In a controlling device, for fluid actuated motors, the combination of a governor spindle; a carrier slidably mounted on the spindle; a weight pivotally mounted on the carrier with the axis of the pivot parallel 20 with the axis of the spindle; a pin rotatively mounted in the weight; a bearing for the pin; a bearing between the weight and the carrier; a mounting fixed against axial movement relatively to the spindle; and a 25 link connecting the mounting with the rotative pin in the weight.

7. In a controlling device for fluid actuated motors, the combination of a governor spindle; a carrier slidably mounted on the 30 spindle; a weight pivotally mounted on the carrier with the axis of the pivot parallel with the axis of the spindle; a rotative mounting on the spindle locked against axial movement; a rotative pin in the 35 weight and a link connecting the mounting and the pin.

8. In a controlling device for fluid actuated motors, the combination of a governor spindle; a carrier slidably mounted on the 40 spindle; a weight pivotally mounted on the carrier with the axis of the pivot parallel with the axis of the spindle; a rotative mounting on the spindle; and a link connecting the weight with the rotative mounting, said spindle having an oil opening leading to the bearing between the spindle and the mounting and to the links.

9. In a controlling device for fluid actuated motors, the combination of a horizontal 50 governor spindle; a carrier slidably mounted on the spindle; a weight forming the centrifugal element of the governor mounted on the carrier; and devices actuated by the weight for moving the weight and carrier bodily axially on the spindle with a movement of the weight under the influence 55 of centrifugal force.

10. In a controlling device for fluid actuated motors, the combination of a horizontal 60 governor spindle; a carrier slidably mounted on the spindle; a weight pivotally mounted on the carrier with its axis parallel with the axis of the spindle; a rotative mounting on the spindle, said mounting being locked 65 against axial movement thereon; and a link

connection between the mounting and the weight.

11. In a controlling device for fluid actuated motors, the combination of a governor spindle; a carrier slidably mounted on the 70 spindle; a weight forming the centrifugal element of the governor mounted on the carrier; devices actuated by the weight for moving the weight and carrier bodily axially with the movement of the weight 75 under the influence of centrifugal force; and a centripetal element for the governor mounted on the carrier.

12. In a controlling device for fluid actuated motors, the combination of a governor 80 spindle; a carrier slidably mounted on the spindle; a weight forming the centrifugal element of the governor mounted on the carrier; devices actuated by the weight for moving the weight and carrier bodily 85 axially with the movement of the weight under the influence of centrifugal force; and a centripetal element acting through the carrier on the weight.

13. In a controlling device for fluid actuated motors, the combination of a governor spindle; a carrier slidably mounted on the 90 spindle; a weight forming the centrifugal element of the governor mounted on the carrier; devices actuated by the weight for 95 moving the weight and carrier bodily axially with the movement of the weight under the influence of centrifugal force; a centripetal element mounted on the carrier and acting on the weight; and a centripetal element 100 mounted without the carrier and acting on the weight through the carrier.

14. In a controlling device for fluid actuated motors, the combination of a governor spindle; a carrier slidably mounted on the 105 spindle; a weight forming the centrifugal element of the governor mounted on the carrier; devices actuated by the weight for moving the weight and carrier bodily 110 axially with the movement of the weight under the influence of centrifugal force; a centripetal element mounted on the carrier and acting on the weight; a centripetal element mounted without the carrier and acting on the weight through the carrier; and means 115 for adjusting the centripetal element mounted without the carrier.

15. In a controlling device for fluid actuated motors, the combination of a governor spindle; a carrier slidably mounted on the 120 spindle; a weight forming the centrifugal element of the governor mounted on the carrier; devices actuated by the weight for moving the weight and carrier bodily 125 axially with the movement of the weight under the influence of centrifugal force; and a lever operating against the carrier and adapted to communicate the action of the governor.

16. In a controlling device for fluid actu-

ated motors, the combination of a governor spindle; a carrier slidably mounted on the spindle; a weight forming the centrifugal element of the governor mounted on the carrier; devices actuated by the weight for moving the weight and carrier bodily axially with the movement of the weight under the influence of centrifugal force; a lever operating against the carrier; and a spring

operating upon the lever and forming the 10 centripetal element of the governor.

In testimony whereof I have hereunto set my hand in the presence of two subscribing witnesses.

RUDOLPH CONRADER.
